FIG. V

FIG. VI

UNITED STATES PATENT OFFICE.

WILLIAM M. SCOTT, OF PHILADELPHIA, PENNSYLVANIA.

STONE-SPREADER.

1,338,161.

Specification of Letters Patent. Patented Apr. 27, 1920.

Application filed May 3, 1917. Serial No. 166,073.

To all whom it may concern:

Be it known that I, WILLIAM M. SCOTT, of Philadelphia, in the county of Philadelphia and State of Pennsylvania, have invented certain new and useful Improvements in Stone-Spreaders, whereof the following is a specification, reference being had to the accompanying drawings.

My invention relates to a self-propelled vehicle which carries means for transporting road materials, such as sand, gravel or crushed stone, and spreading them upon the road. Means may be mounted upon the vehicle for loading the road materials thereon. As a useful adjunct the road material is cleaned before it is spread.

The mechanism for accomplishing these functions may be operated by means of the same prime mover by which the vehicle is propelled, and suitable clutches and connections being provided, whereby the different parts of the device may be separately or simultaneously put into operation as desired.

In the accompanying drawings, which show a preferred method of embodying my invention, Figure I, is a side elevation of the stone spreader.

Fig. II, is a rear elevation showing the details of the spreading device.

Fig. III, is an enlarged view of the disk drive for stone spreader.

Fig. IV, is a plan view of parts shown in Fig. III.

Fig. V, is an enlarged partly sectional view of the rear portion of the machine illustrating more fully certain parts of the spreading mechanism.

Fig. VI, is an enlarged sectional elevation of the disk drive.

I have shown my device as mounted upon, and operating in connection with a motor truck of standard construction, of which the chassis 1, is strong enough to carry the weight of the parts about to be described. It is driven by a sufficiently powerful engine 2, to not only operate the truck, but to simultaneously operate other working parts as desired.

The main engine shaft drives by a suitable connection, as the chain 3, a countershaft 4, by means of which the prime mover transmits its rotation to the various operative devices. These devices comprise a crane for loading road material on the vehicle; a bin for carrying such material

provided with a distributing device, or spreader; and a cleaning device. These I will describe in order.

The crane comprises a standard 5, revolvably mounted upon a hydraulic cylinder 6, and having pivoted to it the arm 7. From the end of the arm is suspended a clam shell bucket 8, suitable for loading road material, such as stone, from piles located at intervals along the road, or from railroad cars. The bucket is supported upon a suitable wire rope 9, which, after being led over and under pulleys, is wrapped around the multiplying pulleys 10, and 11, of which the latter is fixedly mounted upon the hydraulic cylinder 6 while the former is mounted upon the end of the hydraulic piston rod 12. In this way I multiply the throw of the piston by say four, when its movement is transmitted to raise or lower the bucket. The upper end of the piston constitutes a cross head 13, moving in a suitable slideway 14, formed in the standard 5. Operation of the hydraulic cylinder is controlled by means of a pump indicated at 20, driven by a chain drive 21, from the countershaft 4, the connection being subject to an interposed clutch 25, upon engagement of which the rotation of the countershaft 20 is caused to be transmitted to the pump.

The upper part of the crane revolves freely upon its support. Attached to the revolvable part is the geared sector plate 31, meshing with a worm 32, the shaft of which carries opposed bevel gears 33, 33, shiftable by a hand lever 34, to engage alternately the bevel gear 35, on the auxiliary shaft 36, driven by a suitable chain 37, from the countershaft 4, with interposition of a clutch 38, by means of which the operative parts which have just been described may be cut off from operation by the shaft as desired. The arm 7, of the derrick is stayed to the top of the standard by adjustable link stay 40.

On the rear part of the vehicle there is mounted a bin 45, provided with a sloping bottom 46, for the more ready discharge of the material contained therein. The lower part of this bin opens freely into the spreading compartment 48, which extends transversely from side to side of the machine, and discharges from its lower end which is open. To assist in the distribution of the road material this spreading compartment has a series of bolts 49, crossing it near the

opening, the bolts being set in alternating relation to each other, so that the stone falling out of the compartment is thoroughly distributed and separated as it descends, 5 thus permitting effective action of the cleaning device hereinafter described.

To regulate the rate of discharge of the stone, the spreading compartment is divided by suitable partitions 50, into a number of 10 vertical feedways 51, within each of which rotates a vertical feed screw 52. The inclination of the thread of each screw is such that road material will not flow down unless the screw is revolved; but if rotated a free 15 flow may be maintained. These feed screws are mounted on short vertical shafts 53, each of which carries a bevel gear 54, engaging a similar bevel gear 55, set on the transverse shaft 56, which is driven by a chain 57, from the short shaft 58. This latter shaft carries 20 a driven disk 59, the periphery of which is in contact with the surface of the driving disk 60, set on the end of the shaft 61, driven by the chain 62, from the countershaft 4, 25 with interposition of a clutch 65, by which the entire spreader mechanism may be thrown out of operation. The driving disk 60, is slidably mounted upon its shaft under the pressure of a coiled spring 66, whereby 30 the proper pressure is obtained to transmit the power from one disk to the other. The rate of feed is capable of regulation by the lateral adjustment of the driven disk 59, upon its shaft, for which purpose the shaft 35 is provided with a perforated keyway 70, and the disk with a collar which may slide over the keyway and be adjusted thereon by the set screw 71.

The shaft 58, is mounted in sliding bearings 72, and is capable of lateral translation therein by the operation of the bell crank lever 73, one arm of which is connected by link 74, to clutch lever 75. By the last named connections the operation of the 45 clutch lever 75, can instantly disconnect the driving and the driven disks, and occasion the cessation of the action of the feeding mechanism.

For cleaning the stone an air duct 80, is 50 provided coincident with one side of the spreading compartment with which it communicates by means of apertures 82, near its lower end. This air duct 80, communicates by a flue 83, with a fan 84, driven by 55 a chain drive 85, from the countershaft 4, with interposition of the clutch 86. The fan compartment communicates by flue 87, with a dust bin 88, valved at the bottom, whereby the dust which the operation of the 60 fan causes to be drawn from the stone and deposited in the dust bin may be allowed to accumulate until it is from time to time discharged.

The operation of my device is as follows: 65 Road material is from time to time loaded

into the bin by the operation of the crane and bucket. The means for operating the crane from the prime mover of the vehicle have been fully described. The bin being full the vehicle is run along the road upon 70 which the material is to be distributed. In case the material is stone and the surface of the road has already been covered with tar or other binding material, it is preferable to run the vehicle backward over the road 75 in order that the wheels may travel over the clean material which has been spread, rather than over the tarred surface, of the road, and for this purpose a seat 90, is provided on the dashboard, near the steering 80 wheel of the vehicle.

During the feeding operation the spreading screws are rotated at a proper speed to accomplish efficient spreading of the material varying according to the speed at which 85 the vehicle is run over the road. In order that unscreened stone may be used and spread as loaded direct from the railroad cars, the cleaning draft is provided, by the operation of which the suction of the air drawn in 90 through the lower end of the spreading compartment carries with it the fine dust and deposits it in the dust bin, from which it may be from time to time discarded.

Having thus described my invention, I 95 claim:

1. A stone-spreader comprising a vehicle, a stone bin thereon, vertical feed-ways leading from the bottom of the stone bin, vertical feed-screws rotatably mounted in said 100 feed-ways, means for rotating said feed-screws at any desired rate, independent of the motion of the vehicle the inclination of the thread of the feed-screws being such that the material will not flow down the 105 screw unless it is rotated.

2. A stone spreader including in combination, a bin, spreading compartments with which the bottom of the bin freely communicates, a vertical feed screw located in each 110 spreading compartment and terminating at the end of said spreading compartment, and means for operating said feed screws.

3. A stone-spreader comprising a stone bin, a transverse spreading compartment 115 communicating with the bin, wherein the stone descends in a state of distribution and separation, and a pneumatic suction cleaning device communicating with said spreading compartment so as to act on the divided and 120 separated stone descending therein.

4. A stone spreader including in combination, a stone bin, a transverse spreading compartment freely communicating with the bin and having means adjacent its point of 125 discharge for distributing and separating the stone, a suction flue in communication with the spreading compartment adjacent said distributing and separating means, and means for applying suction thereto, where- 130

- by fine dust may be removed from the stone as it passes through the spreading compartment.
5. A stone spreader including in combination, a stone carrying bin, a transverse spreading compartment freely communicating with the bin, vertical feed screws rotatably mounted in said compartment, a pneumatic stone cleaning device communicating 10 with the spreading compartment in the region of its discharge, and means for applying suction thereto, whereby fine dust may be removed from the stone as it passes through the spreading compartment.
6. A stone spreader including in combination, a stone bin, spreading compartments leading from said bin, a feed screw for each compartment, and means for driving the feed screws including a friction disk control device, whereby the speed of the feed 20 screws may be varied.

In testimony whereof I have hereunto signed my name at Philadelphia, Pennsylvania, this thirtieth day of April, 1917.

WILLIAM M. SCOTT.
